CLAIM

The ornamental design for a personal aircraft, as shown and described.

DESCRIPTION

FIG. 1 is a perspective view of the design for my personal aircraft.

FIG. 2 is a left side elevation view of the design.

FIG. 3 is a top plan view of the design.

FIG. 4 is a bottom plan view of the design.

FIG. 5 is a front elevation view of the design; and,

FIG. 6 is rear elevation view of the design.

The right side elevation view is a mirror image of the left side elevation view.
